UNITED STATES PATENT OFFICE.

FRANK I. REMY AND BENJAMIN P. REMY, OF ANDERSON, INDIANA, ASSIGNEES TO
REMY ELECTRIC COMPANY, OF ANDERSON, INDIANA, A CORPORATION.

MAGNETO-ELECTRIC GENERATOR.

983,932.

Specification of Letters Patent. Patented Feb. 14, 1911.

Application filed March 20, 1909. Serial No. 484,831.

To all whom it may concern:

Be it known that we, FRANK I. REMY and BENJAMIN P. REMY, of Anderson, county of Madison, and State of Indiana, have invented a certain new and useful Magneto-Electric Generator; and we do hereby declare that the following is a full, clear, and exact description thereof, reference being had to the accompanying drawings, in which like letters refer to like parts.

The object of this invention is to improve the construction of magnetos, chiefly for the purpose of reducing the cost of making and assembling the same, but also for the purpose of improving the operation of the parts thereof. To this end our invention enables the manufacturer to avoid the making of 48 holes, screws and taps in the construction of so simple and small a thing as a magneto.

The chief feature of the invention consists in making an integral rectangular frame open at the sides, the ends apertured to center bearings, one at each end thereof, an armature inductor shaft insertible there-through, and windings and an inductor therein. The pole pieces are inserted at the sides and the parts are held in place by the magnets overlapping the frame and pole pieces. Thus screws, taps and holes for them are obviated, and the inductor shaft is better centered, and the pole pieces are maintained in better relation thereto than in constructions as heretofore made by employing screws or taps for holding the parts in one position.

The full nature of this invention will be understood from the accompanying drawings and the following description and claims.

In the drawings Figure 1 is a central vertical section through the integral frame, other parts being omitted. Fig. 2 is the same with the bearings, inductor shaft, inductor, windings and one pole piece in place, other parts removed. Fig. 3 is a vertical section through the device on the line 3-3 of Fig. 2, the upper parts of the magnets being broken away. Fig. 4 is an end elevation of the device. Fig. 5 is a section through the entire magneto on the line 5-5 of Fig. 2. Fig. 6 is a horizontal section on the plane cutting the inductor shaft.

with the inductor shaft, inductor and windings removed.

In constructing a magneto as herein set forth, an integral casing 10 is provided, which includes the top and bottom and end portions, the sides being open. The bottom is wider than the top, as shown in Fig. 3. The ends are provided with central openings 11 therethrough, and recesses 12 in the inner surface of the ends are arranged concentrically with the openings 11, so as to receive the bearings 13 for the inductor shaft 14. These bearings 13 consist of a longitudinal portion, the outer end of which projects through the openings 11 in the casing 10, and also a centrally located disk-like portion, which fits in the recess 12. While assembling the parts, these bearings are inserted through a side opening of the casing and put in place, then the windings 15 and inductor 16 are inserted in the casing, and the inductor shaft 14 is introduced through the bearings and inductor 16. This assures the absolute centering of the bearings, by reason of the recesses 12 and the disks forming a part of the bearings, and also there is a longitudinal bearing for the shaft 14. There is no chance for the bearings to be out of alignment or get out of alignment, for the openings 11 and recesses 12 are turned down true in the original construction and likewise the bearings 13.

After the parts above mentioned are assembled, the pole pieces 17 are inserted one on each side. These pole pieces are plates flat on the outside and centrally grooved or cut out on the inside concentric with the disks 19 on the bearings. The pole pieces are not secured by any screw or the like, but rest upon the bottom of the casing and horseshoe magnets 20 are placed down over the top of the casing 10, enveloping the pole pieces 17 and resting upon the bottom of the casing 10, as shown in Fig. 3. This completes the construction without a single screw or screw-hole. The magnets are held in place by the casing and they hold the pole pieces snugly in position, for the pole pieces lie between the disks 19 of the bearings and the magnets, and since the disks 19 are turned true in the original construction, and likewise the curved grooves in the pole pieces,

the pole pieces will always maintain the true relation to the inductor, and on the contrary the inductor, by reason of said bearings, will maintain the true position relative to the pole pieces and the windings 15.

What we claim as our invention and desire to secure by Letters Patent is:

1. A magneto including a casing or frame opening at the sides and the ends provided with bearing openings, bearings insertible in said bearing openings with a disk-like flange thereon inside the casing, an armature and shaft in said bearings, pole pieces within said casing bearing against the disks on said bearings, and magnets overlapping the top of the casing and said pole pieces, whereby said parts will be held in position in the casing.
2. A magneto including an integral casing or frame having a bottom, top and ends, the bottom being wider than the top with bearing openings in the ends and recesses in the

inner surfaces of the ends concentric with said bearing openings, bearings for each end, each bearing formed of a longitudinal portion to project through the bearing openings and a disk-like portion fitting in said recesses so as to maintain said bearings in centered position, an armature and shaft in said bearings, pole pieces in the openings in the sides of said casing with curved sides therein bearing against the disks on said bearings, and magnets overlapping the top of the casing and said pole pieces, whereby said parts are held in proper position in the casing. 35

In witness whereof, we have hereunto affixed our signatures in the presence of the witnesses herein named.

FRANK J. REMY.
BENJAMIN P. REMY.
